GAME

Charles W. Mabey, Indianapolis, Ind.

Application October 16, 1935, Serial No. 45,257

9 Claims. (Cl. 273—139)

This invention relates to a game of chance of the type that may visually indicate results. The invention relates particularly to a game similar to the common and well known punch board, but instead of having paper tickets or the like to be punched out, indicates at once by electrical means the result or answer to the particular station selected and punched by the operator.

An important object of the invention is to provide a new and novel arrangement of elements presenting a series of stations whereby the insertion of an operating member in any one of those stations will give an immediate visual indication as to a predetermined value or answer to be assigned to that station. A further important object of the invention is to provide means whereby those values or answers of the individual stations may be quickly and easily changed by interchanging key cards or plates.

A still further important object of the invention is to provide an extremely simple arrangement of the various elements so that in changing key cards, the various elements will be automatically reassembled in proper sequence in order to permit the operation of the structure. A further important object of the invention is to provide such a combination of elements that may be manufactured and assembled at an extremely low cost of production and at the same time provide a neat and durable game for the amusement of the operator.

These and many other objects and advantages will become apparent to those versed in the art in the following description of one particular form of the invention as illustrated in the accompanying drawings, in which

Fig. 1 is a top perspective view of a structure embodying my invention;

Fig. 2, a longitudinal vertical section on the line 2—2 in Fig. 1;

Fig. 3, a rear end elevation;

Fig. 4, a top plan view with the cover removed;

Fig. 5, a longitudinal vertical section on the line 5—5 in Fig. 4, and

Fig. 6, a wiring diagram.

Like characters of reference indicate like parts throughout the several views in the drawings.

In the form herein shown, I form a rectangular box 10 provided with a cover 11 normally secured thereover by means of a lock bolt 12 engaging over a tongue 13 carried by an arm 14 fixed to and extending downwardly from the under side of the cover 11. In the forward portion of the box 10, here shown as occupying half of the floor area of the box, I place a pad of resilient

material such as sponge rubber 15 to serve as a cushion. A post 16 of any suitable insulating material, here shown as rectangular in shape is vertically positioned on the left hand side of the pad 15 by means of an angle 17 and a like post 18 is vertically positioned on the right hand side of the pad to be there secured by the angle 19. As indicated in Fig. 4, these posts 16 and 18 are staggered in respect to each other in relation to the transverse center line of the pad 15.

On the pad 15 I place a perforated metallic plate 20. This plate 20 has a transverse width greater than the distance between the posts 16 and 18 and is notched so as to engage about those posts whereby the plate 20 must always be positioned the same between those posts when it is removed and replaced. On the top side of the plate 20 is placed a key card or plate 21 which has a limited number of holes 22 punched therethrough to coincide with like positioned holes in the plate 20 thereunder, the card 21 being preferably of the same dimensions as the plate 20 and being provided with notches to engage about the posts 16 and 18 as a means of causing the holes 22 to line up with the corresponding holes in the plate 20 thereunder.

Preferably, although not necessarily so, I provide a spacing member 23 to rest on the card 21 and to be positioned by the posts 16 and 18 by being notched therearound. In the form herein shown, this spacing member 23 comprises essentially a rectangular narrow band following the margin of the card 21 so as to leave the major portion of the upper side of the card 21 exposed and not covered. Where four windows are employed in the cover 11 as indicated in Fig. 1, the member 23 is preferably provided with the central longitudinal and transverse ties 24 and 25 respectively.

Over the spacing member 23 is placed another metallic perforated plate 26 of the same dimensions as that of the members thereunder and likewise positioned by the posts 16 and 18 by being notched therearound. The plate 26 has the same number of perforations as does the plate 20 and is so positioned by the posts 16 and 18 as to have corresponding holes in one, line up vertically with the holes 22 in the card 21 and the corresponding holes thereunder in the plate 20.

Immediately over the plate 26 I place a key card 27 to be positioned thereover by the posts 16 and 18 by being notched therearound so as to have a combination of holes 28 in vertical alignment with corresponding holes in the plates 20 and 26.

26 and 20, with at least one or more of the holes 28 being in alignment with the holes 22 in the card 21, although it is desired to have the arrangement of the holes in the two cards such that all of the holes therein do not come into vertical alignment.

It is to be understood that both the key cards 21 and 27 are of some insulating material. Over the card 27 is positioned another spacing member 29 being a duplicate of the spacing member 23. Then over the member 29 is laid another metallic plate 30 perforated and being an exact duplicate of the plates 20 and 26. Then another spacer member 31 being a duplicate of the spacers 23 and 29 is laid over the plate 30 to have in turn placed on its upper side a metallic perforated plate 32 being an exact duplicate of the other plates 20, 26 and 30.

Over the top plate 32 is laid a paper or other easily perforated insulating sheet 33. This sheet 33 is imperforate and completely covers over the holes through the plate 32. The position of the holes in the plate 32 may be indicated by printing circles on the sheet 33 so that these circles appearing on the upper side of the sheet when the sheet is laid over the plate 32 are in vertical alignment with the holes in that plate. However a preferred form is to employ another plate 34, metallic or otherwise, corresponding exactly to the size and arrangement of the under plates 20, 26, 30 and 32.

All of the various members forming this pile of plates, key cards, and spacing members, are brought compressibly one against the other by means of buttons 35 and 36 on the top sides of the posts 16 and 18, which are turned around over a spacer or pressure member 37 which corresponds exactly to the spacers 23, 29 and 31 in the pile. The resilient cushion 15 permits the application of a yielding pressure.

A metallic pin 38, Fig. 5, here shown as having a handle 39, has proper cross-sectional dimensions as will permit the pin 38 to be inserted through the windows in the cover 11 in any one of the holes there appearing in the top plate 34. The paper 33 is easily punched through by the pin 38 so as to permit the pin to be carried on through the corresponding hole thereunder in the metallic plate 32 and subsequently to permit the pin to be pushed on down through the corresponding hole in the plate 30 thereunder and continued on through until the end of the pin strikes the key card 27. If the pin has been inserted in that hole in the plate 32 which is immediately above a hole in the key card 21 as is the case in the example indicated in Fig. 5, then the key 38 may be pushed on through that hole in the key card 21 to permit the key to travel on through the hole thereunder in the plate 26 to bring the key then into contact with the key card 21.

If a hole there be presented by the key card 21 as again indicated in Fig. 5, the key may be pushed on through that hole in the key card and carried into contact with the bottom plate 20. Of course it will be readily seen that where the key 38 is inserted in some of the holes in the plate 34 below which no holes appear in the key card 27, the key will be stopped by that key card and therefore will only be in contact with the metallic plates 30 and 32 appearing under the paper 33. Where the selection of that hole permits the key to be carried through the key card 27, it may again happen that the key card 21 under the metallic plate 26 has no correspond-

ing hole and therefore the key 38 would be stopped against that key card 21 to again have the pin in contact with the three metallic plates 32, 30 and 26. Thus it is to be seen that various combinations of contacts between the plates and the pin may be arranged by variations in the placing and the number of the holes in the key cards 21 and 27.

Now on the remaining rear portion of the floor of the box 10 back of the cushion 15, I place 10 a plurality of electrical indicating devices, here shown as three in number and comprising the lamps 40, 41 and 42 over which windows 43, 44 and 45 are provided in the cover 11 as indicated in Fig. 1. While the individual lamps themselves may be colored, the windows may be colored instead as indicated in Fig. 1 so that as each lamp is illuminated a different color illumination may be observable from the top side of the cover 11. The plates 20, 26, 30 and 32 each have 20 the respective conducting bands 46, 47, 48 and 49 leading out rearwardly and down to the corresponding binding posts 50, 51, 52 and 53. A suitable source of electric current is provided, two dry cell batteries 54 and 55 being herein shown. One particular wiring hook-up is herein shown as including various combinations of the plates 20, 26, 30 and 32 with the lamps 40, 41 and 42 as will give first, an illumination of the lamp 41 at all times when the pin 38 is in contact with both plates 30 and 32. When the pin 38 passes through the key card 27, then the plate 26 is also brought into the circuit by the pin 38 to cause illumination of one of the other lamps and finally when the pin 38 goes on down 35 into contact with the bottom plate 20 to cause all three of the lamps to be illuminated.

Thus it is to be seen that depending upon the arrangement of perforations in the key cards 21 and 27, two of the lamps may or may not be 40 illuminated.

The arrangement of the wiring to accomplish this result is shown in Fig. 1 as one particular example. From the post 53 a conductor 56 leads to a contact member 57 adjacent which is positioned another contact member 58 so that a suitable key or pin 59' may be inserted from outside of the box 10 to pass between and interconnect the two members 57 and 58 to complete the circuit thereacross. From the member 58 a 50 wire 59 leads to the battery 55. From the other terminal of the battery 55 a conductor 60 is carried to the lamp 41 from which the conductor 61 leads to the binding post 52 thereby furnishing the circuit between the plates 30 and 32 and 55 the lamp 41.

From the binding post 51 a conductor 62 leads to the lamp 40 and from the lamp 40 a conductor 63 leads across through a continuing conductor 64 to the battery 54. From the battery 54 the conductor 65 is carried back to the contact member 58. Also from the binding post 50 a conductor 66 leads to the lamp 42 from which the conductor 67 leads to interconnect with the conductors 63 and 64. Thus when the pin 38 contacts the plate 26 in addition to the plates 30 and 32, a flow of current is established through the lamp 40 to illuminate it as well as the lamp 41. And finally when the plate 20 is additionally contacted by the pin 38, then the lamp 42 is supplied with a flow 70 of current and correspondingly illuminated in addition to the lamps 40 and 41.

Preferably, although not necessary, a foot 70 is attached to the box 10 near the rear end thereof so as to raise that end to give a rearwardly 75.

upward slope to the cover 11 for convenience in operation.

While I have herein shown and described my invention in the one particular form, it is obvious that structural variations may be employed including variation in the number of key cards and contacting plates and the like, all without departing from the spirit of the invention and I, therefore, do not desire to be limited to that precise form beyond the limitations as may be imposed by the following claims.

I claim:

1. An electrically indicating game comprising a plurality of perforate members of electrically conductive material arranged to have perforations in alignment in the several members, a pin insertable in those perforations and thereby electrically interconnecting at least a part of said members, and electrical circuits selectively energized by said interconnecting pin, and signals in the circuit.

2. An electrically indicating game comprising a plurality of perforate members of electrically conductive material arranged to have perforations in alignment in the several members, a pin insertable in those perforations and thereby electrically interconnecting at least a part of said members, and electrical circuits selectively energized by said interconnecting pin, and signals in the circuit, at least one of said members having dissimilar arrangement of perforations to limit the passage of said pin through those perforations to certain of said members.

3. An electrically indicating game comprising a plurality of perforate members of electrically conductive material arranged to have perforations in alignment in the several members, a pin insertable in those perforations and thereby electrically interconnecting at least a part of said members, and electrical circuits selectively energized by said interconnecting pin, and signals in the circuit, and a key card insertable between said members having less perforations than said members to limit the passage of said pin to a member below to those positions wherein the perforation in a member above aligns with a perforation in said card.

4. An electrically indicating game comprising a plurality of perforate members of electrically conductive material arranged to have perforations therein, a pin insertable in those perforations and thereby electrically interconnecting at least a part of said members, and electrical circuits selectively energized by said interconnecting pin, and signals in the circuit, said members being metallic and having identically arranged perforations, means for aligning the plates one over the other, and a key card having less perforations than one of said members insertable between the members for controlling said interconnecting.

5. In a game, a member presented to indicate a plurality of perforations, a plurality of metal-

lic plates thereunder of like arranged perforations, means insulating the plates one from another, a pin for insertion through said member into said perforations, signal devices electrical circuits including said signal devices and said plates closable by said pin interconnecting the plates, and a key card selectively insertable between adjacent plates limiting said pin insertion through the plates to certain of said perforations to change the circuits and signals. 10

6. In a game, a stack of metallic perforate plates, insulating members therebetween, a key card having less perforations than said plates between at least one pair of adjacent plates, means for aligning the perforations of said plates and card, a metallic pin of sufficient length to pass through said perforations to the bottom plate, electrical circuits including the pin and said plates, and an indicating device in each circuit to indicate the circuit closed by the pin. 20

7. A game comprising a box, having a window therein, a stack of perforate metallic plates under the window, electrical insulators between plates in the stack, means for aligning the perforations of the plates, a pin insertable through the window selectively into any one of the perforations presented thereunder, electrical circuits including the separate plates, electrical means in the circuits giving indications upon closing of the circuits by said pin contacting the various plates through their perforations, a key card between selected pairs of plates limiting travel of said pin through perforations in selected plates, and an upper perforatable sheet covering under plates and preventing observation of said card. 30

8. An electrically indicating game comprising a plurality of perforate members of electrically conductive material arranged to have perforations adapted for alignment in the several members, a pin insertable in those perforations and thereby electrically interconnecting at least a part of said members, and electrical circuits selectively energized by said interconnecting pin, and signals in the circuit, at least one of said members having dissimilar arrangement of perforations to limit the passage of said pin through those perforations to certain of said members, and an imperforate sheet over an upper plate perforatable by said pin. 40

9. In a game, a stack of metallic perforate plates, insulating members therebetween, a key card having less perforations than said plates between at least one pair of adjacent plates, means for aligning the perforations of said plates and card, a metallic pin of sufficient length to pass through said perforations to the bottom plate, electrical circuits including said pin and said plates, and an indicating device in each circuit, and an imperforate sheet in said stack over a plate above said card, said sheet being perforatable by said pin. 50

CHARLES W. MABEY.
